SEWING MACHINE

Reuben B. Thompson, Stillwater, N. Y., assignor
to Willcox & Gibbs Sewing Machine Co., New
York, N. Y., a corporation of New York

Application January 7, 1930, Serial No. 419,065

12 Claims. (Cl. 112—132)

This invention relates to a combined sewing machine and ruffler mechanism, the latter forming a part of the sewing machine itself but being so combined therewith that it can be instantly put into or out of action at the will of the operator while the sewing machine is in operation, and regardless of the speed at which it is running.

The work for which principally the machine hereinafter described has been designed is the forming of gathers or ruffles in the upper edge of the back of shirts for men and boys in process of stitching said back between the two plies of the double yoke; but the machine is useful also for other kinds of work in which intermittent or continuous ruffling is required.

An object of the invention is to combine a ruffling mechanism with a standard sewing machine of suitable type without making substantial changes of construction therein; or in other words, to provide a combined sewing machine and ruffling mechanism wherein the organization of the former remains substantially unchanged.

Another object of the invention is to provide a ruffling equipment so designed that, in order to combine it with the sewing machine, the latter requires but few changes, and such as are but slight in extent and easily made.

A further object of the invention is to provide a sewing machine having an intermittent ruffling equipment that is simple in construction, compact, comprising relatively few parts and hence relatively low in cost of construction and of upkeep.

A further object of the present invention is to take the power for operating the ruffling mechanism from a driving shaft on the overhanging arm of the machine above the bed plate, the connection with said shaft being preferably at a point at, or in proximity to, the head of the machine, thus making possible a very compact arrangement of the ruffler-actuating mechanism and its driving connections, all the elements whereof may be located in close proximity to the said arm and to the head of the machine, well above and clear of the work plate.

A further object is the provision of means for throwing the ruffler into and out of action which are more simple in construction and which will operate with greater facility than those heretofore employed for that purpose.

Another object is to provide ruffling mechanism capable of being used with lockstitch sewing machines; and capable, moreover, of being operated successfully in connection with high speed machines of that type.

Another object in view is the production of a much greater output than attainable with combined sewing and ruffling machines now in use, and at a substantially lower cost of maintenance.

Other objects of the invention will be indicated in the following detailed description of a machine constructed in accordance therewith, reference being made to the accompanying drawings which form a part of this specification, and wherein one embodiment of the invention is illustrated as applied to, or combined with, the well-known commercial Willcox & Gibbs high speed lockstitch power-driven sewing machine; but it will be understood that the improvements constituting the present invention, though specially applicable to lock-stitch machines, may also be used to advantage in connection with other types of sewing machines.

In said drawings:—

Fig. 1 is an elevation, partly in section, of the rear side of the machine (that away from the operator);

Fig. 1a is a view similar to Fig. 1, being a completion thereof, showing parts at the left end of the machine not shown in Fig. 1;

Fig. 2 is a top plan view, some of the parts at the head of the machine being omitted;

Fig. 3 is a partial front elevation, some of the parts of the head of the machine being omitted;

Fig. 4 is an end elevation looking at the head of the machine;

Figs. 5, 6 and 7 are vertical sections on lines 5—5, 6—6, 7—7 of Fig. 1, respectively, some of the parts through which said section lines pass being omitted;

Fig. 8 is a horizontal section on line 8—8 of Fig. 7;

Fig. 9 is a horizontal section on line 9—9 of Fig. 3;

Fig. 10 is a view in elevation and section of the ruffler bracket;

Fig. 11 is a vertical cross section of the same on line 11—11 of Fig. 10;

Fig. 12 is a detail in elevation and vertical section showing the ruffler driving connections in their normal positions of rest;

Fig. 13 is a detail in perspective of parts of the ruffler driving connections; and

Fig. 14 is a perspective view of other parts thereof detached from one another.

The main frame of the lockstitch machine shown in the drawings comprises the usual hollow standard 15; the hollow arm or gooseneck 16 through which extends the main shaft 17; and the head 18, which contains the needle-bar crank 55

19 and other parts of the stitch-forming mechanism.

The ruffler, its supporting means and also the means for lowering and lifting it into and out of position for engaging the work will now be described, reference being had specially to Figs. 3, 4 and 9.

The ruffler blade 20, which is or may be of ordinary construction, is carried by a plate 21, herein called the ruffler-foot. Said ruffler-foot is pivotally supported by a narrow bar 22, herein called the ruffler bar, said ruffler bar being rigidly attached at its upper end to a hub 23 fixed by a set-screw 230 upon a horizontal tubular shaft 24 having bearings in a sleeve 25 on the lower part of bracket 35, the latter being attached to the back part of the head 18 of the main frame.

The lower end of ruffler bar 22 occupies a space formed between a lug 27 projecting upwardly from ruffler-foot 21 and an arm 28, also integral with said foot, said parts 27, 22, 28, being all perforated for the passage of pivot screw 26, the perforation in arm 22 being of such size that the shank of screw 26 passes freely through it.

25 Arm 28 also forms one member of a toggle-lever, whereof the other member, arm 29, is pivoted at its upper end to bar 22 by pivot stud 31, and at its lower end has a pin 30 which engages a notch or slot in the upper end of arm 28 (Fig. 4) thus forming a pin-and-slot toggle joint. Toggle lever 28, 29 is the ruffler lifting lever, its main function being to tilt the serrated edge of blade 20 upward, out of contact with the work, when the ruffler mechanism is thrown out of action, and conversely to depress the serrated edge of blade 20 into engagement with the work when the ruffler mechanism is thrown into action. These operations of the ruffler lifting lever are performed automatically at the proper times through connections hereinafter described.

50 Tubular shaft 24 is the ruffler actuating shaft, and in action it has an oscillatory motion as hereinafter described. It is formed with a collar 240 which bears against the end of sleeve 25, the diameter of said collar being such that its circumference is flush with the outer surface of said sleeve. On the other side of said collar, hub 23 is fitted, its outer surface being also flush with that of the collar 240. Said tubular shaft encloses a bolt 32, which is capable of a limited lengthwise movement for the purpose of actuating toggle-lever 28, 29 as presently described.

A spring 39 acts, when free to exert its pressure, to hold ruffler blade 20 in engagement with the work (full line position, Fig. 4). This spring may be variously formed. As shown it is of resilient wire, and is attached at one end to screw 26 having several coils wound around the shank thereof, the other end of said spring being bent around the inner edge of bar 22. Thus spring 29 so exerts its pressure as to keep the toggle lever straightened out, and the serrated edge of blade 20 in contact with the work. It follows that the ruffler blade and foot are held while in operation with yielding pressure.

70 From the foregoing description it will be understood, that the ruffler blade and its support are supported from the oscillatory tubular shaft 24 and when in action are swung back and forth in the arc of a circle whose center is the axis of said shaft. Heretofore in ruffling machines in use, the ruffler blade and its support have been reciprocated back and forth, as by means of a horizontal sliding bar. The above described construction, 75 whereof a distinguishing feature is the radial or

arcuate movement of the ruffler blade and its support, effects a material simplification of parts, especially in respect to the support and its actuating devices, and the means for lowering and lifting the blade into and out of contact with the work. It will be observed that, while the ruffler foot and blade move back and forth in the arc of a circle, yet by reason of the pivotal connection of said foot with ruffler bar 22, and the action of toggle lever 28, 29 and spring 39, the serrated edge of the ruffler blade travels back and forth in a horizontal path, in contact with the work as it lies on the work plate.

75 Toggle lever 28, 29 is actuated to lift the ruffler blade out of engagement with the work by the lengthwise movement of bolt 32 within the tubular shaft 24. When bolt 32 is in the position shown in Fig. 9, which is its normal position, that is, the position it occupies when the ruffling mechanism is not in action, its conical end 33 protrudes beyond the end of shaft 24 and presses against the beveled edge of arm 29, turning said arm on its pivot in such direction as to bend the toggle lever at its elbow 30, thus tilting the ruffler blade upwards at its serrated end. This is the dotted line position of the parts in Fig. 4.

Bolt 32 is moved positively in this direction (to the left in Fig. 9) by means of an arm 34 attached to cross shaft 80 (Figs. 6, 10, 11) hereafter described. Arm 34 bears against a pin 36 (Figs. 3, 6 and 9) which passes through a slot in sleeve 25, and also through a slot in shaft 24, and is tapped into said bolt. When, however, arm 34 is moved to the right, which occurs whenever the operator throws the ruffling mechanism into action, the conical end 33 of bolt 32 is withdrawn from engagement with lever arm 29 to the position shown in Fig. 3; this being effected by the action of a helical spring 38 which encircles the other end of the shank of said bolt. Arm 29 of 40 the toggle lever being thus released from the pressure of the conical head 33 of bolt 32, said lever is bent by the influence of spring 39, thereby tilting ruffler blade foot 21 downward and bringing the serrated edge of blade 20 into position for 45 engagement with the work.

The means for imparting ruffling movements to the ruffler while in action will now be described.

Power for operating the ruffler is taken from the main shaft 17 by means of an eccentric 45 thereon, located in the head of the machine, and an eccentric strap 46 encircling the same (Figs. 3, 4 and 5). The Willcox & Gibbs high speed lock-stitch machine has the main driving shaft in the arm and head thereof, and has on said shaft an eccentric which serves a purpose not needed in a combined sewing and ruffling machine; said eccentric being adjacent to the needle-bar crank 19 before mentioned. By substituting therefor the eccentric 45 with different timing, power is obtained for driving the ruffler mechanism without substantial change in the organization of the machine. The eccentric strap 46 is connected through the intermediary of a pitman 47 and crank arm 48, with a rock-shaft 50, which has bearings in a tubular part 51 of the ruffler bracket 35 (Figs. 1, 2, 11 and 12). The connection is made by means of a hub 49 formed on one end of and integral with arm 48. Said hub 49 is fitted on one end of shaft 50, and is secured in 70 place thereon by means of set-screw 52.

To the other end of rock-shaft 50 is attached a curved crank arm 55, herein called the "segment" (Figs. 1, 5, 6 and 12), its shape being conformed to the arc of a circle. The attachment of seg- 75

ment 55 to rock-shaft 50 is effected by means of a hub 56 (Fig. 1) integral with said segment; said hub 56 being mounted upon rock-shaft 50 and secured thereto by two set-screws 57. By means of eccentric 45, pitman 47, arm 48 and rock-shaft 50 the segment 55 is oscillated continuously so long as the machine is in operation and regardless of whether the ruffling mechanism is in action or not.

Segment 55 has in its face opposite hub 56 a curved slot 58 (Figs. 5 and 6) whose curvature is that of the arc of a circle; in which slot is slidably engaged a block 61 (Fig. 13) pivoted to one end of a link 62, whose opposite end is attached to a crank-arm 63 (Figs. 2, 3, 4, 5, 6 and 12) secured to the tubular rock-shaft 24, by which the ruffler blade is actuated. Block 61 (Fig. 13) is curved to conform to the shape of slot 58 and is pivotally connected to link 62 by screw stud 64.

By means of said link 62 motion is communicated from segment 55 to the tubular ruffler-actuating shaft 24, when the ruffling mechanism is in action. Normally, however, that is to say, while the ruffling mechanism is not in action, block 61 occupies such a position in the lower end of slot 58 that the axis of pivot stud 64 is coincident with that of rock-shaft 50, in which position it is shown in Fig. 12. Therefore, while the parts are in this position the oscillations of rock-shaft 50 and segment 55 communicate no motion to link 62, and the ruffler actuating mechanism remains quiescent. But as soon as block 61 moves off and away from the center of oscillation of shaft 50, link 62 begins to reciprocate, and motion is thereby imparted to shaft 24. The parts are shown in this operative position in Figs. 1, 4, 5 and 6. It is obvious that the further block 61 is moved in slot 58 of segment 55 away from the axis of rock-shaft 50, the greater will be the arc of oscillation of shaft 24, and the longer the throw or ruffling movement of the ruffler blade 20.

It is a feature of the invention that block 61 is always in engagement with slot 58, so that, in putting the ruffler into and out of operation, the action is not like that of a clutch, in which there is an engagement and a complete disengagement of parts. The mechanical connection between the parts 55 and 62 is always complete. What changes when the control mechanism is operated is merely the point of connection between those parts.

It is also a feature of the invention that the power for actuating the ruffler is taken from a point near where the latter is located, which is near the head of the machine, instead of from a point near the other end of the machine, as heretofore. Thereby a substantial gain in compactness is effected, with a consequent saving in the size, weight and cost of the connecting elements. There is also a resulting gain in certainty and ease of operation and in facility of manipulation on the part of the operator.

As will be seen, by reference specially to Figs. 2 and 3, the operation of the ruffler blade by power taken from the main shaft is effected through driving connections that are relatively short and light, and which therefore add comparatively little to the cost, weight and complication of the machine as a whole. The direction of the driving connections is first downwardly from the main shaft by a short pitman 47; thence rearwardly to the back of the machine by a short arm 48; thence along the back of the ma-

chine towards standard 15 by a rock-shaft 50, which need be only a little longer than necessary to clear the head 18 of the machine; thence forward across the machine and under the arm 16 to the front of the machine by link 62; and thence by tubular shaft 24 to the ruffler supporting arm 22. Looked at from above (Fig. 2) the entire system of driving connections presents approximately the outline of a rectangular figure of small dimensions.

Further it will be seen that the controlling means (hereinafter described), whereby the ruffler mechanism is put into and out of action at the will of the operator, are located at the rear of the arm of the machine near the head 15 thereof, and that the connections for operating said controlling means are all on the side of the machine away from the position of the operator.

The means, under control of the operator of the machine, for putting the ruffler into and out of action will now be described. The movement of block 61 in the curved slot 58 of oscillating segment 55, whereby the ruffler is put into or out of action at the will of the operator, is effected through the intermediary of a slide 70, movable vertically between ways formed by the vertical side walls of a housing 71 secured to the hollow arm 16 of the frame (Figs. 1, 2, 7 and 8); said slide being movable at the will of the operator, while the machine is in operation, by means presently to be described. The housing 71 of slide 70 comprises a cover plate 710 (partly broken away in Fig. 1), a top piece 712, and an oil-drip plan 714.

From top piece 712 two stems 94 (Figs. 1 and 7) extend downwardly within the housing, each stem having a screw-threaded upper end which is tapped into said top piece. Each stem 94 is encircled by a strong helical spring 93 and each stem with its spring extends into a socket formed in slide 70. Each spring bears at its upper end against said top piece 712 and at its lower end against the bottom of its socket.

Housing 71 has an opening in the side wall thereof adjacent to the head of the machine (Fig. 1) through which opening extends a member 72 which is attached to slide 70 by screws 76, 76. Said part 72 is shown in perspective, its several parts detached from each other, in Fig. 14. Between ledge 77 and bottom plate 78 of said slide member 72 is a guide-way wherein is positioned the rounded end of link 62 (Figs. 1, 5, 6 and 12). Consequently when slide 70 with its member 72 is moved in either direction the end of link 62 moves with it, thus moving block 61 in slot 58 of segment 55. When slide 70 is in its lowermost position, it being then held by the pressure of springs 93 against stop-pin 73 (as shown in Fig. 7), the end of link 62 is in line with the axis of rock-shaft 50 and the ruffler actuating shaft 24 is consequently motionless. When, however, slide 70 is moved upwardly, compressing springs 93, block 61 and with it the pivot studs 64 are moved off and away from the axis of rock-shaft 50, and the ruffler mechanism is put into operation.

The upward movement of slide 70, carrying with it the free end of link 62, also releases arm 82 of a short horizontal shaft 80 from the downward pressure of said link 62. Said shaft 80 also carries the downwardly projecting arm 34, which, as already described, bears against pin 36 of bolt 32, keeping the latter normally in the position shown in Fig. 9, to lift the ruffler blade 20 out of engagement with the work to the position in which it is shown in dotted lines in Fig. 4. But when

arm 82 of shaft 80 is released from the pressure of link 62, pin 36 of bolt 32 is released from the pressure of arm 34 of said shaft 80 (Figs. 3 and 9), whereupon said bolt is retracted by its spring 38 to the position shown in Fig. 3. Consequently arm 29 of the ruffler lifting lever is released from the pressure of head 33 of bolt 32, and the ruffler blade 20 is swung down by the pressure of spring 39, into its working position shown in full lines in Fig. 4. Springs 38 and 39 are normally under compression and ready to act as soon as they are released from the pressure of the stronger springs 93.

Thus the upward movement of slide 70 effects two results, one by positive action, the other automatically. First, it brings about, by shifting the position of block 61 in slot 53, an active relationship between the driving shaft 17 of the sewing machine and the ruffler-actuating shaft 24, the mechanical connection between those parts being always complete; and secondly, it effects automatically, through the action of springs 38 and 39, the depression of the serrated end of the ruffler blade into contact with the work.

The connections for moving slide 70 upwardly at the will of the operator in order to throw the ruffler into action are illustrated in Figs. 1, 2 and 7. As there shown, a bell-crank lever 85 is pivoted at 86 to a lug 75 (Fig. 2) on the side of the slide housing 71, one of the arms of said lever being pivotally connected to slide 70 near the lower end thereof by means of a link 87. Said link 87 connects pivotally, by means of screw stud 89 (Figs. 1, 7 and 8) with slide 70. Screw stud 89 passes through a slot in cover plate 710. The other arm of bell-crank 85 is connected by a link 88 with one arm of a second bell-crank 90, pivoted at 91 to standard 15; and to the other arm of lever 90 is attached a rod 92 (Fig. 1a) leading to a suitable actuating device, such as a treadle or a knee-piece, not shown. In Fig. 1, the bell-cranks 85 and 90 and connected parts (including slide 70) are shown in full lines in the positions they occupy when the ruffler is in action, and in dotted lines in the positions they occupy when the ruffler is out of action, at which time slide 70 is in contact with stop-pin 73.

When slide 70 is moved upwardly by the means just described, or by other suitable means, it compresses springs 93, so that said springs, when free to act, move slide 70 downward to the position shown in Fig. 7, in which position of the parts, the axis of the pivot stud 64 on slide block 61 is in line with that of shaft 50, the ruffler mechanism is stationary, and the ruffler blade is tilted upwardly out of contact with the work, as already explained.

For the purpose of adjusting the throw of the ruffler blade, so as to produce ruffles of different widths, an adjustable stop screw 95 is provided (Figs. 1, 3 and 7). Said screw 95 has a milled head, and its screw-threaded shank passes through and engages a threaded hole in top piece 712 of the slide housing 71; a milled edge lock nut 96, also in engagement with stop-screw 95, being provided for holding said stop screw in its adjusted position. The position of stop-screw 95 determines the limit of the upward movement of slide 70; and this in turn determines the throw of the ruffler blade, as already explained. Thus, to form wider ruffles stop-screw 95 is adjusted upwardly, and to form narrower ruffles it is adjusted downwardly.

The treadle operated connections for lifting the presser-bar 970 (shown in Fig. 1) are of the

construction usually employed in the Willcox & Gibbs high speed lockstitch machine. They comprise the bell-crank lever 97 having a lifting finger at its end which engages with the presser-bar, and a connecting rod 98 attached to lever 97 at one end and to a second bell-crank lever 99 at the other, the latter having a downwardly extending rod 101, leading to the operating treadle, not shown.

From the foregoing description it will be understood that the ruffler mechanism comprises—

(a) What may be regarded as "driving means" located on and supported from the head and overhanging arm of the frame of the sewing machine, said means beginning with the main shaft 15 and the eccentric 45 thereon and terminating at the rear side of said head and arm of the frame in the segment 55 which is oscillated continuously so long as the machine is in operation;

(b) Driving connections from said driving means to the ruffler blade 20, said connections being mounted on and supported from the head and overhanging arm of the frame and beginning with the block 61 slidable in slot 58 of the segment 55, and extending from said block at the rear side of the machine beneath the overhanging arm of the frame to and along the front of the machine at the head thereof and thence depending to and terminating with the ruffler-foot 21 and the ruffler blade attached thereto. 30

(c) Means under control of the machine operator for shifting the point of connection between said driving means and driving connections, that is, shifting said slide block 61 in the slot of segment 55 from a position in which no movement is imparted to the driving connections to a position for imparting movement thereto and vice versa, said control means beginning with a suitable knee-piece or treadle (not shown) and terminating in the slide 70 and parts thereon which constitute a guide-way engaged by the rounded end of the link 62. Except for the connections to the knee device, the parts constituting such control means are supported from the overhanging arm of the machine at the rear side 45 thereof. 40

(d) Means associated with said driving connections for automatically moving the ruffler blade into or out of operative position for engagement with the work according to whether 50 the driving connections are, or are not, being actuated from the driving means.

It will be understood that the mechanism hereinbefore described and illustrated in the drawings is merely one form in which the invention may be embodied, and is not to be taken as limiting the scope of the invention as defined in the appended claims.

What is claimed as new is:

1. The combination with a sewing machine 60 having an overhanging arm and a sewing head at the end thereof, of a driving shaft journaled on said arm; ruffling mechanism; actuating connections thereto from said shaft all mounted on said head and arm and including a rock-shaft 65 journaled on said head and located at the back of the machine, means located at said head of the machine for driving said rock-shaft from said driving shaft, and other means actuated by said rock-shaft and extending beneath said overhanging arm from the back to the front of the machine; and means under control of the operator for throwing said ruffling mechanism into and out of operation. 70

2. The combination with a sewing machine 75

having a standard, a hollow arm connected at one end with said standard and at the other with the head of the machine, and having a shaft extending through said arm, of a ruffling device; 5 actuating mechanism therefor; driving connections receiving power from said shaft at said head of the machine; and means for throwing said driving connections into and out of operative relation with said actuating mechanism, said means 10 comprising an oscillating segment located at the back side of the machine near the head thereof and a link extending beneath said arm connected at one end with said ruffler-actuating mechanism and having at its other end a pin-and-slot connection 15 with said segment.

3. In a combined sewing and ruffling machine, the combination with the arm and head and with a driving shaft extending along the former and into the latter, of an oscillating segment driven 20 from said shaft; a ruffler blade; a rock shaft by which said blade is carried; a connecting link attached at one end to an arm of said rock shaft and at the other adjustably engaged with said segment; and means operable by the operator 25 during the running of the machine for moving the free end of said link relatively to the axis of said segment.

4. The combination with the driving shaft of a sewing machine, of an oscillating member receiving motion therefrom; ruffling mechanism including an actuating shaft; a link attached at one end to an arm on said actuating shaft and at its other end being in adjustable engagement with said oscillating member, the point of engagement 30 being substantially in line with the axis of oscillation thereof when the ruffling mechanism is not in action; and means under the control of the operator for moving the free end of said link away from the axis of oscillation thereby to put 35 said ruffling mechanism into action.

5. The combination with a sewing machine, a ruffling device and connections for actuating the ruffling device from a driving shaft of the sewing machine; of means for throwing said ruffling device into and out of action, said means comprising a slide mounted in a fixed guideway on the frame of said machine and movable to different positions to correspondingly vary the movement of the ruffling device; means under control of 45 the operator for moving said slide while the machine is in operation in the direction to throw the ruffling device into action; and a spring for returning said slide to its normal position.

6. The combination with a sewing machine, of 50 a ruffling device comprising a ruffler blade and a pivoted support therefor; driving connections for operating said ruffling device from a shaft of said sewing machine; means under control of the operator for throwing the ruffling device into and 55 out of action, said means comprising a slide mounted in ways of the sewing machine frame; and connections for tilting said ruffler blade support downward when the ruffler is thrown into action and upward when it is thrown out of action, said last named connections being also actuated by said slide.

7. The combination with a sewing machine 60 having an overhanging arm, a sewing head at the end of said arm and a driving shaft on said arm and head, of ruffling mechanism and driving connections therefor all mounted on said arm and head and including a rock-shaft located at the rear of the machine, means for driving said

rock-shaft from said driving shaft, and other means actuated by said rock shaft and extending across said arm from the rear to the front of the machine.

8. The combination with a sewing machine 5 having an overhanging arm, a sewing head at the end of said arm and a driving shaft journaled thereon, of ruffler mechanism comprising a ruffler actuating shaft and driving connections therefor all mounted on said arm, said connections comprising actuated members extending and transmitting power from said driving shaft along the rear side of said head to said ruffler actuating shaft.

9. The combination with a sewing machine and 15 its driving shaft, of ruffling mechanism comprising a tubular actuating shaft; an arm attached thereto; a ruffler blade pivotally attached to said arm; a lifting lever for turning said blade on its pivot; a spring for holding said blade yieldingly in 20 contact with the work while the ruffler is in action; means under the control of the operator for putting said tubular shaft into and out of operative relation with said driving shaft; a bolt 25 movable within said tubular shaft; and connections for actuating said bolt when the ruffler is put out of action to tilt said blade out of contact with the work.

10. The combination with a sewing machine 30 and its driving shaft, of ruffling mechanism comprising a tubular actuating shaft; a ruffled blade pivotally attached to an arm fixed to said shaft; a lifting lever for turning said blade on its pivot to an operative and an inoperative position in respect to the work; a bolt movable lengthwise 35 within said tubular shaft for operating said lever to tilt it out of operative position; a spring for returning said lever to operative position when released by said bolt; and means under the control of the operator for putting said actuating 40 shaft into and out of operative relations with said driving shaft and for simultaneously moving said bolt in one direction or the other.

11. The combination with a sewing machine 45 having an overhanging arm, a sewing head at the end thereof and a driving shaft journaled on said arm, of ruffling mechanism; driving connections therefor all mounted on said overhanging arm and actuated from said driving shaft and including a rock-shaft located at the back 50 of the machine, means located at the head of the machine for driving said rock-shaft from the driving shaft, and other means actuated by said rock-shaft and extending beneath said overhanging arm from the back to the front of the machine; and means adapted to be actuated by the operator while the machine is in operation for throwing said ruffling mechanism into and out 55 of operation.

12. The combination with a sewing machine 60 including its driving shaft, of ruffling mechanism comprising an oscillatory shaft located at the front of the machine, an arm attached to said shaft, a ruffler blade attached to the free end of 65 said arm, and driving connections comprising actuated members extending and transmitting power from said driving shaft along the rear side of the machine to said oscillatory shaft whereby said blade is swung back and forth in the arc 70 of a circle.
